C. J. HEISER,

PROTECTIVE DEVICE FOR ELECTRICALLY HEATED UTENSILS.

APPLICATION FILED FEB. 13, 1919.

1,323,471.

Patented Dec. 2, 1919.

UNITED STATES PATENT OFFICE.

CHARLES JOSEPH HEISER, OF LOS ANGELES, CALIFORNIA, ASSIGNOR TO PACIFIC MANUFACTURING AND ELECTRIC COMPANY, OF LOS ANGELES, CALIFORNIA, A COPARTNERSHIP.

PROTECTIVE DEVICE FOR ELECTRICALLY-HEATED UTENSILS.

1,323,471.

Specification of Letters Patent.

Patented Dec. 2, 1919.

Application filed February 13, 1919. Serial No. 276,874.

To all whom it may concern:

Be it known that I, CHARLES JOSEPH HEISER, a citizen of the United States, residing at Los Angeles, in the county of Los Angeles and State of California, have invented a new and useful Protective Device for Electrically-Heated Utensils.

My invention relates to the control of an electric current by means of a fuse operated by the conduction of heat from an electric heating element to a fuse contained in a chamber immersed in a liquid.

The principal object of my invention is to provide a novel form of fuse controlling an electric circuit; which circuit heats a liquid through the medium of an electric heating element; the heating element being immersed in the liquid or in contact with the utensil containing the liquid.

The invention consists in the construction and novel combination and arrangement of parts hereinafter described as illustrated in the accompanying drawings and pointed out in the claims hereunto appended. It is not intended that the invention be limited to specific shapes and arrangements of utensils and heating elements shown in the drawings.

In these drawings which are for illustrative purposes only:

Figure 1, is a view of an electric heating element in a vessel such as may be used with a hot water tank, showing a method of applying the fuse from the top of the vessel.

Fig. 2, is a view of a utensil with an electric heating unit in same showing a method of applying the fuse from the bottom of the utensil.

Fig. 3, is a view of the fuse and chamber on an enlarged scale as compared to Figs. 1 and 2.

Fig. 4, is a cross section along the line A—A', Fig. 3.

Fig. 5, is a cross section along the line B—B', Fig. 3.

In the drawing 1 is a casing or vessel under normal conditions being entirely filled with a liquid, except for that portion occupied by the fuse chamber 4 and that portion

which may be filled by the heating element 2, the casing being entirely inclosed except for the openings 22 and 23, which may be connected respectively to the top and bottom of a storage tank containing a liquid. In the casing is a heating element 2, above mentioned which may be of any desired shape, the only requirement being that the arrangement of same be such that the end of the fuse chamber 4 containing the fuse 5 may be applied in close proximity to same. A small space may be left between the fuse chamber 4 and the heating element 2, or if desired the fuse chamber 4 may be in contact with the heating element 2, by a relatively small area of the one touching the other.

Energy is supplied from the electric circuit 5—6, the current passing through the conductor 5 to the terminal stud 7 and thence through the electric heating unit 2 to the stud 8; thence through the fuse 5 in the chamber 4 to the terminal stud 9 and thence through the conductor 6 to the other side of the power circuit.

The circuit in the fuse itself is from the terminal lug 10, through the lead-in conductor 11 to the fuse 5; thence through the other lead-in-conductor 12 to the terminal lug 13. The lead-in-conductors are substantially insulated from each other and from the tube 19 by the insulating material 15. The insulating barrier (16) projects down between the points of juncture of the fuse 5 and the lead-in-conductors 11 and 12. A cap 17 lined with the insulating material 18 is arranged to slip on the tube 19. The whole fuse mechanism slips in the chamber 4 from which it can readily be removed.

In the case of Fig. 1, this removal is accomplished by removing the terminal stud wing nuts 8 and 9. The terminal board 14 is provided as shown.

Two methods are shown in the drawings of applying the fuse chamber 4 to utensils. In Fig. 1 the fuse chamber 4 is inserted from the top of the utensil and in Fig. 2 the fuse chamber 25 is shown inserted from the bottom of a utensil.

While the above described fuse has vari-

ous uses it is particularly useful in connection with the installation of electrical heating devices to existing forms of hot water tanks.

5 Fig. 1, is illustrative of such heating device in which the opening 22 may be connected to the top of a water tank and the opening 23 to the bottom of same; the water in the tank being heated by virtue of a 10 circulation of water set up when the heating element 2 is in operation, under which conditions hot water will flow from the opening 22 to the top of the tank and cold water to flow from the bottom of the tank to the 15 opening 23. The water in both the tank and the casing is under whatever pressure exists in the water mains to which it is assumed the tank is connected.

It will be noted that if the heating element 2 should be allowed to operate for a 20 sufficient length of time and little or no water be drawn off from the tank a condition will arise where steam will form in the top of the vessel (1). On account of 25 the concentrated form of electric heating element usually employed the element will not operate for any considerable length of time under these dry conditions without serious damage resulting which means usually that the heating element will become 30 destroyed.

It will be noted that under normal conditions the fuse can not reach a temperature materially in excess of the temperature of 35 the liquid in which it is immersed.

Under the conditions set forth above, however, where, due to the formation of steam the water is forced down from the top of the element it will soon reach a point where 40 the top portion of the element and the entire fuse chamber is no longer surrounded by a liquid. Under these conditions there being no longer a liquid present to conduct away the heat generated in the heating element 45 2 the temperature of the heating element will rise to a point considerably in excess of the normal operating temperature. Due to the fact that the heating element 2 and the fuse and the fuse chamber 4 are 50 mounted in close proximity to each other this heat will become conducted from the heating element 2 to the fuse chamber 4 and thence to the fuse 5, which will then melt. The point at which this melting 55 occurs can be determined by the kind of material used in the manufacture of the fuse 5.

As the fuse 5 is in series with the element 2 the melting of same opens the electric 60 circuit and current ceases to flow.

In Fig. 2 I show another application of the heat fuse chamber 25 containing heat fuse 5. In this instance the fuse chamber

25 in the utensil 3 is in thermal contact through a limited area with the heating element 24. It will be noted that this thermal contact may be accomplished in any desired manner. The consideration is that the conduction of heat through the area of contact between the element 24 and the fuse chamber 70 25 will not under normal operating conditions exceed materially the conduction of heat from the fuse chamber 25 to the liquid. In other words the temperature of the fuse chamber under normal operating conditions 75 must not materially exceed the temperature of the liquid.

The operation of the heat fuse under the conditions which would apply if the level of the water receded materially below the tip 80 of the element 24 will be the same as described heretofore in the case of Fig. 1, except that by virtue of a thermal contact existing between the fuse chamber 25 and the element 24 a more rapid conduction of 85 heat would take place to the fuse 5 and it would operate quicker.

I have heretofore set forth in these specifications the manner of removing the fuse mechanism from the chamber 4. It will be 90 noted that when this mechanism is removed the cap 17 is carried with it. After this entire mechanism is removed it will be noted that the cap 17 can in turn be removed from the tube 19, which leaves the fuse 5 exposed. 95 Under this condition it will be noted that a new fuse can readily be applied to the ends of the lead-in-conductors 11 and 12.

The fuse 5 may be attached to the lead-in-conductors 11 and 12 by being sweated 100 on same or by being crimped on same or in any convenient manner.

What I claim is:

1. In combination; walls forming a vessel; an electric heating element so placed as 105 to heat a body of liquid in said vessel; and a heat responsive device adapted to open the circuit of said heating element whenever the temperature of said heat responsive device exceeds a predetermined value; 110 said device being so placed as to be normally immersed in said liquid in close proximity to said element.

2. In combination; walls forming a vessel; an electric heating element so placed 115 as to heat a body of liquid in said vessel; and a heat responsive device adapted to open the circuit of said heating element whenever the temperature of said heat responsive device exceeds a predetermined 120 value; said device being so placed as to be normally immersed in said liquid in close proximity to said element; said heating element and said heat responsive device being so situated with relation to each other that 125 said heat responsive device is partially out

of thermal contact with said liquid whenever any portion of said heating element is out of thermal contact with said liquid.

3. In a water heater a containing vessel; an electric heating element; lead-in conductors forming part of the electric circuit and connected with the terminals of a fuse, said fuse being contained in a chamber

which under normal operating conditions is immersed in the water contained in said vessel; the points of juncture of said conductors with said fuse being insulated from each other by means of an insulating barrier.

CHARLES JOSEPH HEISER.
